UNITED STATES PATENT OFFICE.

HENRY L. PITMAN, OF WESTFIELD, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed August 30, 1924. Serial No. 735,085.

This invention relates to improvements in mechanism for transmitting motion to a fan-folded work-web having carbon-sheets interleaved between its several plies, for the purpose of advancing the same to the printing line of a typewriting machine, such as the standard Underwood billing machine, and to permit this feeding motion to take place during the line-spacing action of the platen in a positive manner.

In the type of machine of which the Underwood typewriting machine is an example, it is customary to provide an extension table in back of the platen in a manner to support a carbon-carrier which is movably guided thereon and which holds a plurality of carbon-sheets which are interleaved between the plies of the fan-folded work-web. Means are provided for swinging the platen-frame to a position where, upon casting off of the pressure feed-rolls from the platen, the work-web can be drawn upon practically horizontally, and thus be pulled around the platen to a usual gage, so as to measure the length of a printed form on the web, and to prepare this form for a severing action along the edge of a tearing-off knife. In order not to cut off any portion of the carbon-sheets at the same time the carbon form is severed, means are provided in the type of machine under consideration for retracting the carbon sheets back of the platen just previously to pulling the form towards the gage.

Owing to the inertia produced by the weight of the carbon-carrier, the carbon-sheets and the web, it frequently happens that the web and carbon-sheets are not fed along during the rotation of the platen incidental to this line-space action, the platen slipping relatively to the web, so that it becomes necessary to overcome this slipping tendency.

One of the main objects of the present invention is to accomplish this foregoing result by novel mechanism which is so arranged and designed that it will positively operate intermittently, and as often as the paper-carriage makes a complete reciprocation to create slack upon the work-web and the carbon-sheets interleaved therewith in back of the platen just prior to the rotation of the platen as it is being line-spaced by the usual line-spacing lever. The mechanism for looping or creating slack upon the web is

manually-controlled and functions to place the work-web under slack without causing any simultaneous movement upon the platen, and to automatically restore it to normal position at the end of the typing action which has taken place against the platen.

Another object of the present invention is to provide simple, efficient and inexpensive means for looping the carbon-sheets at the same time that the web is being looped, and to accomplish this purpose it becomes necessary to reverse the action that has heretofore taken place in the process of looping the web with the carbon-sheets interleaved between its plies. Other devices operate to create a loop upon the composite web, but in doing so those devices which employ the carbon-carrier have provided means for moving the carrier, so as to cause it to move the web upon itself, thereby creating the loop. But in the present invention it is the web which directly impresses movement upon the carbon-carrier; in either event the looping of the web cannot take place without causing the carbon-carrier or other means, acting as a substitute therefor, to move in the direction of and towards the platen, because during such movement the carbon-sheets held upon the carrier are moved with the web, it being understood that the web comes from a source of supply back of the typewriting machine whereas the carbon-sheets are mounted directly upon the carbon-carrier and initially lie at the rear of the table which extends in back of the typewriter.

Another object of the present invention is to provide a carbon-carrier with a brake yieldably engaging the table upon which the carrier is movably guided, so as to prevent any retrograde movement on the part of the carrier, without which the loop could not be formed upon the web when the carrier is advanced toward the platen, while a pulling action is exerted upon the web, as is the case with the present invention. The usual web clamp mounted upon said carbon-carrier is supported, together with the brake, upon manually-controlled means upon the carrier which function to simultaneously disengage both the clamp and the brake from the base plate of the carbon-carrier and the table, respectively.

In carrying out the hereinbefore mentioned objects, means are provided which are

positioned in back of the platen in such a manner that during the shifting of the paper-carriage back to initial position to the point where it begins its movement (incident to the typing action which takes place during the depression of the usual type-writer keys), this means becomes active and operates to bow or arch the web which is stretched out longitudinally upon the table, due to the action of the tensioning means which holds the web onto the platen, and the brake mounted on the carbon-carrier which frictionally holds the carbon-carrier stationary. As the web is arched it moves vertically, and in doing so it drags along the carrier against the tension of the spring-brake, thereby advancing the web and interleaved carbon-sheets a short distance in order to create slack upon the web and carbon-sheets just prior to the platen being rotated to line-space the web.

Other features and advantages will hereinafter appear.

In the accompanying drawings,

Figure 1 is a side-elevation, partly in section, of the present invention mounted upon a billing typewriting machine.

Figure 2 is a cross-sectional view, partly broken away, taken on line A—A of Figure 1, looking in the direction of the arrow.

Figure 3 is a perspective view of a yieldable wedge.

Figure 4 is a side view, partly in section, of the line-spacing mechanism.

Figure 5 is a view similar to Figure 2, but showing a modification thereof.

In the drawings, which are merely illustrative of the invention, 10 designates the platen of a standard Underwood typewriting billing machine, or the like, which is rotatably mounted upon a carriage 10^a directly over the apron 11 which forms a continuation of the usual paper shelf 12, a platen-shaft 11 being journaled in the usual platen-frame 13, which, in this type of invention, is mounted on a swinging frame (not shown) for a purpose hereinafter explained.

The cylindrical platen 10 is rotated during its line-spacing action, through the usual gearing, by a ratchet wheel 14 which is rotated by a spacer slide 15 operated by a spacer-lever 17, said spacer-lever having its hub 16 suitably pivoted and terminating in a handle 18, which is movable in a guide 19. 20 designates the usual type-bars which swing in the direction of the platen so as to engage the same, and which carry the usual type surfaces 21. 22 designates a tearing-off knife which is positioned just above the printing line and at a point convenient for cutting off each length of printed form of a composite or fan-folded work-web A. The usual feed pressure rollers 23 and 24 are provided for applying tension against the platen to press the web against the platen so

as to assure the web being carried along during the line-spacing of said platen. A gage-bar 26 is operatively secured at an inclination upon the front shelf 25 of the machine and adjustably mounted upon this bar is a 70 gage 27 which is secured in juxtaposition by means of the usual thumb screw 28. A release lever 29 is also shown, which, when depressed in a conventional manner, allows the platen-frame to be manually lifted to position the web held by the platen, so that it occupies the same level with the table 36, to allow the web to be conveniently manipulated and held while the operator is manually retracting the carbon-carrier towards the rear of the table, thereby separating the carbon-sheets from the printed form that is about to be gaged and then detached.

Upon a rail 30 the paper-carriage 10^a is movably guided at one point rectilinearly so as to have a forward and backward stroke thereupon, the forward stroke being intermittently impressed thereon during the successive depression of the typing keys, and the backward stroke being imparted thereto in the act of manually shifting the paper-carriage back to initial position just after or during line-spacing action of the platen. A rear rail 31 is engaged by the rollers 32 which are journaled upon brackets 33 secured upon the table 36, the rail 31 being mounted upon a main frame 34 which forms an extension of the usual typewriting machine. A turn-rod 37 is mounted on arms 38 at the rear of the table and trained thereover is a fan-folded web A, after it leaves its source of supply. The longitudinal sills of bar 39, together with the brace rods 40, make up the table. The carbon-carrier is movably guided upon the table by means of grooved rollers 41 mounted thereupon which roll upon the rails 35 mounted upon the table longitudinally, these rollers being journaled in holders 42 secured to the base plate 43 of the carbon-carrier. Stepped uprights 44 are also mounted upon the carbon-carrier in the usual manner, and support in staggered and superimposed relation, the carbon-holding fingers 45 which project into the folds of carbon-sheets 46 which are interleaved with the plies of the composite or fan-folded web A.

The web A is arranged to be pressed in contact with a lip 60^a by means of a spring-finger 60 mounted upon the clamping arm 59 of a bell-crank lever 59^a, which is pivoted at 61^a and has an arm 57 arranged to be actuated by a handle-bar 50 having a finger-piece 51. The carbon-carrier is arranged to be manually impelled upon the table 36 by means of a standard 47 secured thereto which terminates in the forwardly-extending arm 48 which is also formed with a finger-piece 49 spaced in advance of the other finger-piece 51. The handle-bar 50 is formed

with an elongated slot 53 in which projects slidably a pin 52 mounted upon the handle-bar 48. A retractable spring 55 has one end secured to a lug 56 on the standard 47, and 5 has its other end similarly secured upon a lug 54 formed upon the handle-bar 50, this spring serving normally to hold the finger-pieces 51 and 49 in spaced-apart relation.

10 58 designates an adjustable stop engaging the rail 35 and serving to limit the backward movement of the carbon-carrier, so as to position it initially. A spring-brake is provided in the shape of a pressure spring 61 15 which bears against the rail 35 having its inner end fixedly secured at 62 upon the arm 59 of bell-crank-lever 59^a. This spring-brake offers resistance against the forward movement of the carbon-carrier, and at the 20 same time prevents the retrograde movement thereof.

The mechanism for creating slack upon the web will now be described. Extending transversely beneath the table 36 is a track 25 34^a supported upon the main frame 34, as shown particularly in Figure 2. Arranged to be secured preferably between the ends of the track 34^a is a wedge or cam which is mounted upon the track as follows. A base 29 plate 65 is adjustably secured upon the track 34^a by means of fastener pins 64, which pins also project into an elongated slot 66 formed upon this base plate 65, the pins having heads 67 overlying the latter. The arrangement of the slot and pins is such as will permit the base plate 65 to be secured adjustably of the track 34^a. A boss or standard 68 is formed upon the bar 65 and carries an outwardly-extending pivot pin 69 upon 35 which is fulcrumed one end of a lever 70 acting as a wedge, cam, or inclined plane, the outer end of this lever 70 being beveled at 71, and this beveled edge resting upon the track 34^a so as to dispose the lever at a downward 40 inclination. To assist in yieldably mounting this wedge lever 70, a lug 72 is formed laterally upon this lever, and pressing against the lug downwardly, is a flat spring 73 secured at 73^a upon the standard 68, as 45 shown clearly in Figure 3.

A roller 74, which may be made of rubber, is journaled upon a pin 75 mounted in a post 76, the upper end of which is secured as at 55 88, upon a cross-bar or follower 77, said cross-bar having downwardly-extending arms 78 secured thereto at opposite ends, as shown at Figure 2, which arms have curved portions 79 which are secured at their outer ends upon lugs 80 formed right angularly upon levers 81, the latter being fulcrumed upon pivot pins 82 mounted upon posts 84 suspended from the table 36, the posts 84 being secured by fasteners 85 upon the table. Leaf springs 83 are coiled around the pins 82, and are held in pressed engagement upon

the lever arms 81, so as to normally position the roller 74 upon the track 34^a. It may be desirable to provide clearance between the roller 74 and the track 34^a which can be done by providing a stop 89 upon one or both of 70 the arms 78, which stop is caused to rest upon the rail 35, as shown in Figure 2, until the roller engages the cam about to be described, and then the stop is lifted out of engagement with said rail.

75 86 designates a pin secured at the inner end of the table 36 and serving to limit the forward movement of the carbon-carrier.

The operation of the invention is as follows: The web leaves its source of supply, 80 is turned over the rod 87 and extends upon the carbon-carrier with the carbon-holding fingers 45 projecting into the folds of the web, the carbon-sheets 46 being interleaved between the plies of this web. Beyond the 85 carbon-carrier the web is stretched horizontally so as to contact with the follower 77, said web being stretched through the agency of the usual feed pressure rollers 23 and 24 which hold it against platen 10, the spring-brake 61 serving to hold the carbon-carrier as the web is being stretched. It will be understood that the pressure rollers 23 and 24 exert more tension than the spring-brake 61, this being rendered necessary at the time 90 the mechanism is operated to bow or arch the web, as shown clearly in Figure 1, in which event either the tension rollers 23 and 24 or the spring-brake 61 must be displaced, and it is designated that the brake 61 shall be displaced, as it is necessary to hold the web in proper relation against the platen by means of the feed-rollers 23 and 24 for line spacing purposes, as is well understood by 95 those skilled in the art.

100 During the typing action the paper-carriage 10^a moves from right to left, carrying with it in the same rectilinear direction, and while it is thus making its forward stroke, the platen 10, the table 36, and the auxiliary frame consisting of the follower 110 77 and the roller 74. Finally the carriage reaches the end of its forward stroke, and it becomes necessary to shift it back to normal position from left to right. The typist 115 does this manually, and in the Underwood typewriting machine, the typist takes hold of the line-spacer handle 18 and pushes the same from left to right at the same time that the paper-carriage is being shifted from left to right, back to normal position. The spacer slide 15 operates in a well known manner to impart motion to the gears 14 which are effective to rotate the platen 10, which rotation will cause the web to be advanced a distance of one or more line space 120 or spaces, as the case may be, thereby causing the carbon-carrier to advance, so as to carry along the carbon-sheets with the web, up to the printing line of the machine. 125 130

However, during the backward or return stroke of the paper-carriage, the roller 74 starts to move from one end of the track 34^a to the other end thereof, from left to right, and in due time the roller rides over upwardly upon the wedge or cam 70, thereby elevating the lever arms 81 against the tension of the springs 83, and by this movement causing the follower 77, which extends transversely across the table 36 to upset, arch or bow the web and interleaved carbon-sheets, as shown in dot and dash lines in Figure 1. The roller 74 moves to the extreme upper point of the wedge 70 and then drops off and continues its movement to the extreme right end of the track 34^a, at which point the paper-carriage has completed its backward stroke and is positioned again normally and is ready to make its forward stroke during the ensuing typing action.

Immediately as the web is strained and arched by the follower 77, owing to the fact that the feed-rollers 23 and 24 hold the web stationary against the platen 10, a pull is exerted upon the carbon-carrier by the web as it moves vertically of the table in a plane at right angles to the direction to which it is longitudinally fed by the platen. As the carbon-carrier thus moves toward the platen the carbon-sheets undergo the same arched curvature that has been impressed upon the web by the follower 77, the spring-brake 61 being overcome yieldably, the latter movement of the carbon-carrier being induced by the web A. The moment the roller 74 drops down in the back of the wedge 70, the spring 83 serves to restore the lever arms 81 to normal horizontal position, thereby retracting the follower 77 to normal position just slightly above the table 36, and playing out or placing under slack the web and interleaved carbon-sheets which are thus suitably looped, the spring-brake 61 serving to prevent the retrograde movement of the carbon-carrier, so that the loop of the web is disposed between the carbon-carrier and the platen.

The paper-carriage moves again from right to left, as typing action proceeds, until it reaches the end of its forward stroke, and due to this forward movement of the paper-carriage, the roller 74 is starting to move on the track 34^a from right to left. It will be understood that the pest 76, as shown in Figure 1, is spaced out of contact or adjacent the side of the wedge lever 70, so that during the forward movement of the carriage the roller 74 moves directly beneath the wedge 70 until it engages the beveled edge 71 thereof and lifts this end of the wedge upwardly until the roller has passed beyond the wedge, at which time the leaf spring 73 snaps the lever back in contact with the track 34^a; the roller 74 finally

reaches the left end of the track 34^a at which time it is positioned for the next backward stroke of the paper-carriage.

Before this backward stroke occurs, the typist has again manipulated the spacer handle 18, and has line-spaced the platen 10 rotatively, so as to advance and take up the loop portion B' of the web and interleaved carbon-sheets, and in doing so the platen does not have to overcome the inertia of the carbon-carrier, which still remains stationary, so that the platen cannot slip relatively to the web, and is disposed to move the web a proper number of lines up to the printing line of the machine. In the same way the paper-carriage is successively reciprocated incidental to each typing action and each line typed upon the web, until a printed form on the web has been sufficiently typed to call for the separation of this form from the other forms.

In order to separate this typed form, the typist releases the release-lever 29 of the swinging platen-frame in a manner well understood in the art, and swings the platen-frame upwardly, and at the same time releases the feed rollers 23 and 24 from engagement with the platen; by virtue of this action the typed printed form is disposed horizontally and is then pulled between the platen and the feed rollers 23 and 24, and its leading edge is advanced over the gage-bar 26 and made to contact the gage 27. As the printed form is being gaged, however, the typist with one hand engages the finger-pieces 51 and 49 simultaneously, and while the other hand pulls the finger-piece 51 forward, the finger-piece 49 instantly disengages the spring-brake 61 from frictional contact with rail 35 and also disengages the spring-finger 60 from the lip 60^a. As this action takes place the typist pushes the handle-bars 50 and 48 backwardly which results in pushing backwards the carbon-carrier which undergoes this movement independently and relatively to the web, the carbon-sheets, however, being retracted with the carbon-carrier until the leading ends thereof have been retracted to a point just above the printing line to allow the printed typed form to be detached. The printed typed form is then drawn against the edge of the tearing-off knife 22, and is cut off while the carbon-sheets are still interleaved with the next preceding printed form and are disposed in a plane with the apron 11 of the paper-shelf 12, which position they occupy when the carbon-carrier engages the stop 58 after having been pushed back as far as it can be.

The action then proceeds in the same way hereinbefore described, and during each backward stroke of the paper-carriage the carbon-carrier has intermittently advanced, and each time it advances, the web is placed

under slack. It may thus be seen that the mechanism provided herein for looping the web operates in time with the platen, so that the steps of operation of taking up the loop and forming the loop are successive; because the platen, when it is lined-spaced, rotates and advances the loop portion of the web just as soon as it is finished; and while the paper-carriage is still moving backwardly a fresh loop is formed upon the web instantaneously.

In some types of typewriting machines the typing action makes the paper-carriage move from left to right, and then of course, the looping action must take place synchronously, and this makes it necessary to position the cam or wedge 70 in a manner shown in Figure 5, where it inclines in just the opposite direction to that shown in Figure 2. The operation otherwise is the same as has already been explained.

Of course the length of the lines typed on any printed form may be varied, so that the distance the paper-carriage moves during its forward and rearward stroking may be lengthened or shortened accordingly. Still it is necessary in this event to operate the web-looping mechanism during the backward stroke of the paper-carriage. So it is necessary to adjust the bar 65 longitudinally of the track 34^a at the proper point to assure that before the paper-carriage completes its backward stroke, the roller 74 will have completely traversed the inclined plane of wedge 70, so as to timely actuate the web-looping mechanism.

Variations may be resorted to within the scope of the invention, and portions of the improvements may be used without others.

Having thus described my invention, I claim:

1. In a typewriting machine, the combination of a letter-feeding carriage, a platen mounted therein, a web arranged to be advanced by said platen, and means movable relatively to the carriage for slackening said web, said slackening means connected to said carriage to be controlled thereby.

2. In a typewriting machine, the combination of a letter-feeding movable carriage, a platen revolubly mounted therein, a movable carbon-carrier, and means actuatable by said carriage and engaging the work-web for actuating said carbon-carrier to produce a slack in the web.

3. In a web-typewriting machine, the combination of a paper-carriage, means for imparting a reciprocatory movement thereto, a platen rotatably mounted in said carriage, a carbon-carrier, means on said carrier holding the work-web, a friction brake against the tension of which said carbon-carrier moves, means controlled by said paper-carriage and engaging said web for effecting a slack in the web, and means for

releasing said brake, to allow said carrier to be retracted relatively to the web.

4. In a typewriting machine, the combination of a frame, a carbon-carrier movably guided thereupon, web-feeding means positioned in advance of said carrier, the web being tensioned against said feeding means, and means movable at an angle to the course of movement of said carrier and imparting a forward movement to said carrier effective to loop the web between said carrier and web-feeding means.

5. In a typewriting machine, the combination of a frame, rails thereupon, a carbon-carrier guided upon said rails, a spring brake for the carrier, manual means for actuating said carrier, means for releasing said brake, means causing said carrier to move in a plane at right angles to the rails, and means moving with the last-named means and engaging the work web for looping the same against the opposition of said brake so as to create slack upon said web.

6. In a typewriting machine, the combination of a frame, a paper-carriage, means engaging one end of the work-web for pulling the same along, means for holding the web stationary, friction means engaged by said web back of said carriage and actuating the latter when said web is arched, web-arching means having a forward and backward stroke in unison with said carriage, and means becoming active during the forward stroke only of said carriage for actuating said arching means.

7. In a typewriting machine, the combination of a paper-carriage, a follower reciprocating with said carriage, a work-web being normally stretched in contact with said follower and arched thereby during the reciprocatory movement of the carriage, and a spring restoring said follower to normal position whereby the arched portion of said web is placed under slack.

8. In a typewriting machine, the combination of a table, a paper-carriage connected with said table, the work web travelling longitudinally of said table, means on said carriage for feeding said web along, a carbon-carrier movable on said table, a track at right angles to said table, a follower having rolling contact with the said track, means tensioning said web, and means disposed along the track and engaged by said follower for causing said web to pull upon said carrier while said web-feeding means is inactive.

9. In a typewriting machine, the combination of a paper-carriage, a table moving therewith, the work-web moving over said table, means on said carriage for line-spacing said web, a frame pivotally mounted below said table, means controlled by said carriage for elevating said frame, means engaging said table and tensioning the web.

thereupon, and means controlled by said frame as it is elevated for causing said web to pull said tensioning means, said frame being automatically returned to normal position whereby said web is put under slack.

10. In a typewriting machine, the combination of a paper-carriage, a table secured therebeyond, a frame pivoted beneath said table, a follower extending transversely over said table, means connecting said follower upon said frame, means for manually shifting said carriage, the work-web being stretched over said table in contact with said follower, said frame moving pivotally to cause said follower to loop said web, and means operable during the movement of said carriage for actuating said frame.

11. In a typewriting machine, the combination of a frame, a track thereupon, a cam on said track, a table moving longitudinally of said track, a web moving longitudinally of said table, a frame moving with said table, a paper-carriage for said table, means controlled by said frame for stretching said web, and means controlled by said cam for actuating said frame.

12. In a typewriting machine, the combination of a frame having a track, a table moving alongside said track, a frame pivotally suspended upon said table, a roller projecting from said frame and movable from end to end of said track, a cam disposed between the ends of said track and engageable by said roller so as to tilt the frame, a work-web on said table, means connected to said table for tensioning said web in advance thereof and holding it stationary, a carrier movably guided on said table and releasably holding said web, and means controlled by said frame as it is tilted for advancing said carrier to cause it to loop said web.

13. In a typewriting machine, in combination, a frame having a track, a cam disposed between the ends of said track, a frame making a forward stroke from end to end of said track, a post projecting from said frame, a roller journaled in said post and riding over said cam during the forward stroke of said frame, means moving the work-web in one direction, means holding said web against retrograde movement,

means operable upon the engagement of said roller with said cam for looping said web, means causing said frame to make a backward stroke and effective to carry said roller along therewith during this stroke, and means whereby said roller during its reverse movement on said track may displace said cam.

14. In a device of the kind described, the combination of a table, a carbon-carrier movably guided thereover, a base plate on said carrier, means for clamping a web upon said base plate, a spring-brake on said carrier frictionally engaging said table as said carrier moves, means on said table for moving said carrier, and means on said carrier for simultaneously releasing said clamp and brake.

15. In a device of the kind described, the combination of a table, a carbon-carrier movably guided thereupon, a plurality of carbon-sheets held upon said carrier and projecting beyond said table, a spring-brake on said carrier for tensioning the movement thereof upon said table to hold said carbon-sheets against retrograde movement, manually-controlled means for intermittently engaging said carbon-sheets for moving the latter vertically and also moving the carrier horizontally, said carbon-sheets being placed under slack as said last-named means are inactive, a work-web contacting with said carbon-sheets and moving therewith, a revolute platen, and means for tensioning said web and carbon-sheets against said platen for feeding along the looped portion of said carbon-sheets and said web.

16. In a device of the kind described, the combination of a table, a carrier movably guided thereupon, a base plate on said carrier, a bell-crank lever fulcrumed on said carrier, a clamp carried by said bell-crank lever for pressing a work-web upon said base plate, a spring-brake fastened upon said bell-crank lever and frictionally engaging said table, a handle for moving said carrier, and manually-controlled means on said handle for operating said bell-crank lever to disengage said clamp from said base plate and said brake from said table.

HENRY L. PITMAN.
